Primary Examiner — Daniel J Domino(74) *Attorney, Agent, or Firm* — McDonnell Boehnen Hulbert & Berghoff LLP(57) **CLAIM**

We claim the ornamental design for a display screen or portion thereof with icon, as shown and described.

DESCRIPTION

The sole FIGURE is a front view of a display screen or portion thereof with icon showing our new design.

The broken lines in the FIGURE show a display screen or portion thereof and form no part of the claimed design.

1 Claim, 1 Drawing Sheet(56)
